(57) **CLAIM**

The ornamental design for a planter necklace, as shown and described.

DESCRIPTION

FIG. 1 is a front, right side perspective view of a planter necklace;

FIG. 2 is a front elevational view thereof;

FIG. 3 is back elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front, right side perspective view of a second embodiment of a planter necklace, each of the planters shown being identical to the planter shown in FIGS. 1-7; and,

FIG. 9 is a front, right side perspective view of a third embodiment of a planter necklace, each of the planters shown being identical to the planter shown in FIGS. 1-7.

The broken line portions are shown for environmental purposes and form no part of the claimed design.

The perspective views of FIGS. 1, 8 and 9 are shown in reduced scale.

Because the material of the article is knitted or crocheted, the remote side of the article is normally visible through the fore side of the material but is not shown in the figures for ease of illustration.
